TENT CONSTRUCTION

Thomas Condit Powers, Upper Darby, Pa., assignor to Powers and Company, Philadelphia, Pa., a corporation of Delaware

Application September 21, 1937, Serial No. 164,838

5 Claims. (Cl. 135—15)

My invention relates to an improved tent construction, and particularly to strengthening and reinforcing of the tent at corners where the tension of guy ropes or other supporting ropes is transmitted to the tent proper.

Heretofore a great deal of difficulty has been encountered in tents, particularly concession tents and the like, which are subjected to severe usage, in the pulling out of the corner at the point where the guy ropes are secured to the tent.

It is the primary object of my invention to provide an improved corner construction which will strengthen and reinforce the tent at the point where the guy ropes are attached. It is a further object of my invention to provide an improved corner construction wherein the strains incident to supporting the tent will be distributed and will not all come at the extreme corners where the guy ropes are attached.

It is a further object of my invention to provide an improved corner construction for tents which will distribute the strains incident to supporting the tent along ropes secured to the tent for the purpose of taking this tension.

I have illustrated my invention in preferred form in the accompanying drawing, wherein the figure illustrates the corner portion of the tent with my improvements applied thereto.

In the drawing, reference numeral 1 represents the sloping roof of the tent. Reference numeral 2 represents a trimming extending along the front of the tent. Reference numeral 3 indicates the end wall of the tent and 3a is a trimming at the end wall. The triangular portion 4 is the portion extending from the end wall proper to the roof.

At the edge 8 of the tent where the roof 1 meets the trimming 2, the canvas is folded and the tent rope 5 is sewn into this fold in such a way that the material of the tent is in tight surrounding relation to the rope, although the rope itself is not sewn to the material of which the tent is made. At the top 9 of the end wall a similar tent rope 6 is sewn into a fold in the material, and the tent rope 7 is likewise sewn into a fold along the edge 10, where the triangular portion 4 of the end wall meets the roof 1. The tent ropes 5 and 6 extend from corner to corner of the tent, and the tent rope 7 extends up over the ridge pole and down to the other corner at the end of the tent. These ropes 5, 6 and 7 are intended to take the strain incident to the support of the tent by means of guy ropes at the corners, and thus relieve the material of the tent from any substantial strains.

Heretofore it has been the practice to run the ends of the ropes 5, 6 and 7 at the corners around an eyelet or through a ring to which the guy rope is secured. In this form of construction the tension on the tent comes at one place 5 on each of the ropes 5, 6 and 7, and under severe strain the corners frequently pull out, because the ropes are unable to withstand the tension. In my improved construction, I provide free end portions or extensions 11, 12 and 13, respectively, 10 of the ropes 5, 6 and 7, which extensions are spliced into a reinforcing rope which is laced to the tent ropes proper outside of the fold in which they are enclosed. This reinforcing rope is substantially larger and stronger than the tent 15 ropes 5, 6 and 7 in order to take the strain at the corner and distribute it along the tent ropes.

In the drawing, two such reinforcing ropes are shown. The first, indicated by the reference numeral 11, extends along the edge 10, where the roof 1 meets the triangular part 4 of the end wall. This rope 11 is secured to the tent in the following manner: The free end portion or extension 12 of the rope 7 is first spliced into the end portion 13 of the rope 11, in such a way that the 20 ends of the two ropes substantially coincide. The other end 14 of the rope 11 is then laced with heavy cord 19 to the outside of the fold enclosing the tent rope 7. The body of the rope 14 is then likewise laced to the fold enclosing the tent rope. 30 The lacing 19 surrounds strands of the rope 14 and likewise surrounds the tent rope 7. The lacing is drawn very tight so as to hold the rope 14 securely against the outside of the fold in such a way that strains or tension on the rope 14 will 35 be transmitted to the tent rope 7 throughout the length of the rope 14. The extension of the rope 7 and the end portion of the reinforcing rope 11 which have been spliced together, is then passed through the corner ring 15, brought back along 40 the edge 10, and likewise securely laced to the fold. If desired, instead of securing the rope 11 to the tent as above described, the extension of the rope 7 and end of the reinforcing rope 11 are spliced together, then passed through the 45 corner ring 15, then brought back and spliced to the standing part of the rope 11, and the whole then secured to the fold along the edge 10 in the manner described. It is important that whatever means is used to secure the rope 11 to the 50 tent should hold it tightly in contact with the tent on the outside of the fold enveloping rope 7, so that any strains which come on the rope 11 will be transmitted to the rope 7 along the part where the two ropes are in juxtaposition.

The extensions 17 and 18 of the tent ropes 5 and 6 are spliced into second reinforcing rope 16 in a somewhat different manner. Instead of being spliced to the end of reinforcing rope 16, 5 extension 17 is spliced into rope 16 at the center, and instead of looping back around corner ring 15, as does extension 12 of rope 7, it is carried around the corner in the direction of rope 6. The extension 18 of the rope 6 is likewise spliced 10 to the center of the reinforcing rope 16 and carried around the corner in the direction of the rope 5. This reinforcing rope 16 likewise extends through the ring 15 and after extensions 17 and 18 of ropes 5 and 6 have been spliced into 15 it the rope 16 is secured to the edges 8 and 9 of the tent by lacing 19 in the same way the rope 11 is secured to the edge 10. It will be understood, of course, that the other corners of the tent have a similar arrangement of reinforcing 20 ropes to which the ropes along the edges of the tent are spliced.

When the tent is to be put into use, guy ropes are secured to the corner ring 10, and the roof is supported by a ridge pole in the usual manner. 25 The tension strains now involved in supporting the tent are transmitted from the guy ropes through the ring 15 to the reinforcing rope, and the ropes of the edges of the tent. The reinforcing ropes, however, take a large part of the 30 tension which is transmitted to the other ropes throughout the length of the reinforcing rope. Thus instead of having all the strain of the support of the tent fall at one point on the ropes in the edges of the tent, it is distributed along them, 35 and the corner is strengthened.

I have found that tents embodying my improved corner construction will withstand much greater strain than other forms of tent known in the art, and the life of the tent will, of course, 40 be much greater.

It will be understood that my improved construction can be used to advantage wherever there is a tension on the corner of a tent, and I do not limit my improvement to use at the corner where guys are attached. In circular tents having 45 a single center pole, for instance, the ropes in the seams of the tent could be secured to the top ring in the same manner as I have illustrated in the drawing.

I claim:

1. A tent construction comprising walls having intersecting edges, tent ropes sewn into folds at the edges and coextensive with the edges into which they are sewn, the said tent ropes having 55 extensions at their ends, a ring at the intersection of said edges through which said extensions pass, a reinforcing rope laced to the said edges outside of said fold with the lacing surrounding the said tent ropes, said reinforcing

rope also extending through said ring, the extension of the first mentioned ropes being spliced into the reinforcing rope outside of the fold whereby strain on the ring will be taken by both 5 ropes.

2. A tent corner construction comprising tent ropes sewn into folds in walls of the tent, said tent ropes having extensions at their ends, a corner ring through which said extensions pass, a reinforcing rope also extending through said 10 ring, the extensions on the tent ropes being spliced into the reinforcing rope outside of the fold, the reinforcing rope being laced to the outside of said tent rope with the lacing surrounding the said tent rope whereby strain on the ring 15 will be taken by both the tent and reinforcing ropes.

3. A tent corner construction for tents having a sloping roof and end wall comprising a tent rope sewn into a fold at the eave of said roof, 20 another tent rope sewn into a fold at the intersection of the end wall and roof, and another tent rope sewn into a fold of the end wall, each of said tent ropes having an extension at the end thereof, a corner ring through which said extensions 25 pass, reinforcing ropes also extending through said ring, the extension of said tent ropes being spliced into the reinforcing ropes, the said reinforcing ropes being laced to the tent outside the said folds with the lacing tightly 30 surrounding the tent ropes whereby strain on the ring will be taken by the reinforcing ropes and the tent ropes.

4. A tent corner construction comprising a tent rope sewn into a fold of the tent and having 35 an extending end portion, an external reinforcing rope having a free end portion, said extension on the tent rope and free end portion of the reinforcing rope being spliced together, the spliced together portions of said ropes being laced to a 40 fold enclosing the tent rope by means of lacing which tightly surrounds the tent rope.

5. A tent construction comprising walls having tent ropes sewn into folds along lines of tension when the tent is in use, said tent ropes having 45 extensions at the ends thereof, a corner ring through which the said extensions pass, and reinforcing ropes into which the said extensions are spliced, the said reinforcing rope also extending through said corner ring and being 50 securely laced to the tent rope along the outside of said folds by lacing which tightly surrounds the tent rope whereby strain on the ring will be taken by both the reinforcing and tent ropes and strain on the reinforcing rope transmitted 55 to the tent rope throughout the length of the reinforcing rope.

THOMAS CONDIT POWERS.
